Application December 18, 1931, Serial No. 581,872

10 Claims. (Cl. 49—2)

Our invention relates to methods and machines for use in the manufacture of incandescent lamps and similar articles and more particularly for use in the said manufacture for sealing the mounts into bulbs. An object of our invention is to provide a method and machine whereby the mount is sealed into the bulb without leaving any substantial waste glass or cullet.

Our method of sealing requires the use of bulbs having necks of predetermined length and the rims thereof substantially square. Our machine holds the bulb in a head, as by vacuum, and lowers into the neck thereof at the sealing position a mount comprising stem tube, leading-in wires, exhaust tube and filament. Fires which revolve around this head are then allowed to play on the rim of the bulb neck until said neck is softened whereupon a set of jaws bend said rim over the edge of the end of the stem tube. The continuing operation of the fires fuses a portion of the bulb neck and of the stem tube into the seal which is later stretched by pulling down the bulb while the exhaust tube is still held by the head.

Other features and advantages of our method and machine will be apparent from the following description of a species thereof and from the accompanying drawings.

Referring now to the drawings, Fig. 1 is a vertical section through the incandescent lamp sealing-in machine of our invention; Fig. 2 is a fragmentary plan view thereof; Fig. 3 is a side elevation of one of the heads, a portion of which is in section, which supports the lamp parts; Fig. 4 is a perspective view of the bulb holding portion of the head; Fig. 5 is a sectional perspective view of the mount holding portion of the head; Fig. 6 is a side elevation of the incandescent lamp in various stages of the sealing-in operation; Fig. 7 is a dis-assembled perspective view of the clutch which controls the rotation of the head; Fig. 8 is a side elevation of the bulb neck bending device; Fig. 9 is an exploded perspective view thereof; and Fig. 10 is a perspective view of the bulb neck stretching device.

Referring now to the drawings and particularly to Figs. 1 and 2, it will be seen our machine comprises principally a turret 10 on which are mounted a number (sixteen) of heads which support the lamp parts. The turret is rotated intermittently in a counter clockwise direction in such a manner that the heads rest in each of the positions numbered one to sixteen in Fig. 2 for a short space of time. The turret is rotated or indexed by spider 11 which is supported by ball bearing 12 on pedestal 13 and is, like the turret, attached

to the centrally located tubular shaft 14. Of the rollers 15 on pins 16 in the outer edge of the spider only one is engaged when the turret is indexed by the curved portion 17 of cam 18. As each head is represented by a roller the indexing motion consists in advancing the roller to the position occupied by the preceding roller. While the heads are not in motion they are held in position by the presence of the uncurved portion of cam 18 between two of the rollers. Drive shaft 19 on which the cam is mounted is operated by worm wheel 20 in mesh with a worm gear on shaft 21 which is operated by motor 22 through belt 23 and a pair of pulleys not shown. Drive shaft 19 also operates cam shaft 24 through bevel gears 15 and 26 and vertical cam shaft 27 through bevel gears 28 and 29.

The description of our machine now follows the order of the various operations, the first of which occurs at the position designated as number one. At this position the bulb 30 is loaded either manually or mechanically into the lower part of the head shown in Figs. 3 and 4. The bulb rests neck up on collar 31 on the upper edge of sleeve 32 which is slidably mounted on spindle 33. Friction insert blocks 33' which are forced against the spindle by screw 34 in split collar 35 hold the sleeve in place. The spindle is kept from turning in hollow shaft 36 by bar 37 which connects the heads together in pairs by connecting collars 38 of two adjacent heads. The vertical position of the spindle and consequently the bulb is fixed by roller 39 on pin 40 in collar 38 which rides on track 41. Spring 42 which operates between the collar and washer 43 keeps the roller engaged with the track. The bulb is held in the collar by vacuum which enters from the passage 44 in the spindle through holes 35' in said collar. A circular passage 45 about shaft 36 in the turret communicates with the vertical passage in the spindle through holes in both the spindle and the shaft and is connected through pipe 46 to a port (Figs. 1 and 2) in the lower half 47 of the rotary valve. The port is at this position located below passage 48 in the upper half 49 of the rotary valve which is connected to the vacuum line through pipe 50 and valve 51. Spring 52 forces the faces of both halves together preventing leakage.

The head after receiving the bulb is indexed to position two and then to position three. At one of these positions the mount is inserted into the head as at either position the head is prepared to receive it. The mount is preferably of so-called tipless construction and comprises the

stem tube 53, the exhaust tube 54, the leading-in wires 55 and the filament 56. The exhaust tube of the mount is thrust between jaws 57 and 58 until said tube is against pin 59 and in such a vertical position that the lateral flange or flared-out portion of the stem tube 53 is against the jaws 60. Although jaws 60 are open they are in a position to engage the stem tube. Pin 59 is attached to jaw 57 and operates in a slot in jaw 58. Jaws 57 and 58 are operated by spring 61 (Fig. 5) and operate about pin 62 in clamping blocks 63 and 64 screwed to bracket 65. This bracket which supports all of the mount holding portion of the head is slidably mounted in bracket 66 on the upper surface of the turret and is located vertically by roller 67 on pin 68 which engages stationary cam 69. All similar rollers of each of the heads (Fig. 1) are engaged by this cam which is mounted on shaft 70 between spring 52 and collar 71 which allows its vertical position to be adjusted by turning wheel 72. The adjustment occurs as spindle 73 attached to wheel 72 is screwed in or out of shaft 70. The lamp parts will then be located with reference to each other as shown in section A of Fig. 6.

The head is now indexed into position four and by so doing lowers the mount into the bulb to the position shown in section B of Fig. 6. The vertical movement is produced by the roller 67 entering the lower part of cam 69 and is accompanied by another movement produced by said cam which closes jaws 60 and concentrically locates jaws 57 and 58. In producing these latter movements the raised portion 74 (Fig. 3) of the cam which engages roller 75 on a pin in the end of slide 76 is terminated allowing said slide to be moved back by spring 77. This spring is stretched between a post 78 in the slide and another post 79 in cover plate 80 which holds said slide within the ways in bracket 65. Jaws 60 are operated, like levers 82 which centralize jaws 57 and 58, by a pin (not shown) corresponding to pin 83 which moves in the diagonal slot 84 corresponding to slot 85. The jaws are also pivoted on a pin in bracket 65 like the levers which pivot on pin 86. The levers engage jaws 57 and 58 through pins 87 and have their ends supported as do both pairs of jaws by plate 88 attached to the end of bracket 65.

At position four the burners 89 and 90 are ignited and caused to rotate about the bulb with their flames playing on the edge of the bulb neck. The burners are mounted on opposite sides of plate 91 through rods 92 and brackets 93 and are rotated by gear 93' through the clutch shown in Fig. 7 on the end of shaft 36 to which said plate is also attached. When the clutch is engaged as at this position, protuberance 94 of slide 95 is within a notch in ring 96 attached to gear 93' and will cause the shaft 36 to be rotated as collar 97, in which the slide is held, is attached to shaft 36. The slide is forced to engage ring 96 by spring 98 which operates between another protuberance 99 of slide 95 and plate 100 attached to collar 97. When the clutch is disengaged, slide 95 is moved by pressure on roller 101 on pin 102 in said slide until out of engagement with the notch in ring 96. Gears 93' of each of the heads of our machine are operated through gear 103 (Figs. 1 and 2) slidably mounted on shaft 14 and pinned to gear 104 which is supported through ball bearing 105 on table 106. This gear is in mesh with gear 107 on shaft 108 which is operated by vertical cam on shaft 27 through sprockets 109 and 110 and

chain 111. The gas mixture which leaves the burners is ignited by a pilot light (not shown) and is carried to the burners (Fig. 3) through passages in rods 92, brackets 93 and plate 91. As the passages in the plate are directly above 5 a circular passage 112 in plate 113 which is forced against the lower surface of plate 91 by spring 114 the burners will receive the gas mixture during the entire revolution. The thrust of spring 114 is taken by ball bearing 115 on the 10 lower surface of the turret. The gas mixture is conducted to each plate 113 (Figs. 1 and 2) of the heads of our machine by hoses 116 which connect to individual ports in the lower half 47 of the rotary valve. A passage 117 in the upper 15 half 49 of the valve which receives the mixture from the air main 118 and gas main 119 through pipe 120 and valves 121 and 122 conducts the mixture to the ports.

The fires continue to play upon and rotate 20 about the bulb while the head is indexed through positions five, six and seven, but are kept from rotating on entering position eight. The clutch operating the fires is caused to disengage, as previously described, at this position by the striking of roller 101 against block 123. The fires take such a position that the jaws 124, 125 and 126 of the bulb neck bending device shown in Figs. 8 and 9 can operate between them. This device operates on the edge of the bulb neck 30 bending it over the lateral flange or flared-out portion of the stem tube as shown in section B of Fig. 6. The entire device is operated by movement of lever 127 about pin 128 in standard 136 which moves sub-slide 137 horizontally by engagement with said sub-slide through roller 138 on a pin in the end of said lever. With the movement of the end of said lever to the right, both slide 139 and sub-slide 137 are advanced, the former sliding in standard 136 in which it is held 40 by plates 140 and 141 until the head of screw 142 in bracket 143 strikes the head of screw 144 in bracket 145. The sub-slide 137 then slides in the slide in which it is held by plates 146 and 147 against the pull of spring 148 which extends 45 between a post 149 in the sub-slide and another post 150 in the slide. The sub-slide advances until screw 151 is against post 150 at which position jaw 124 which is carried thereby and jaws 125 and 126 are against the neck of the bulb. 50 The movement of levers 152 and 153 which carry jaws 125 and 126 about pins 154 is produced by the separate movement of the sub-slide which causes rollers 155 on pins 156 to enter the spread portion of slots 157 in plate 158 carried by the 55 sub-slide. Lever 127 is actuated by lever 159 (Figs. 1 and 2) which engages the end of rod 160 through collar 161, spring 162 and collar 163 and which is operated about a pin in bracket 164 by the engagement of roller 165 held thereby 60 into the ways of cam 166. Rod 160 is connected to said lever 127 through yoke 167 and pin 168 and the complete device is covered by a guard 169. The neck of the bulb having been bent the device returns to its former position and the head 65 indexes on to another position.

With the indexing of the head out of position eight, the clutch control roller 101 leaves block 123 and pin 166' (Fig. 7) in collar 97 strikes lever 170 which retards the rotation of the head until 70 the clutch has engaged. When the clutch has engaged, lever 170 is swung about pin 171 in the table 106 against the action of spring 172 on bolt 173 in said lever. The spring acts between the lever and bracket 174 extending from the table 75

and swings said lever back when the head has indexed until it is against stop block 175. No other mechanism other than the fires operate upon the bulb while the head indexes through positions 9, 10, 11 and 12 and the bulb neck is fused to the stem tube as illustrated in section D of Fig 6.

The next indexing which carries the head into position thirteen causes the fires to be extinguished and the burners to take the stationary position shown in Fig. 1. The fires are extinguished by the rotary valve, the port leading to this head in the lower half 47 of which now comes under the solid portion of the upper half 49 instead of under passage 48. The burners are kept from rotating by the striking of the clutch operating roller 101 against the raised part 176 of the track and the insertion of pin 166' (Figs. 1 and 10) between guide plates 177 and 178 of the track. The device located at this position stretches or shapes the seal by pulling down the bulb while the exhaust tube is still held by the head as shown in section E of Fig. 6. The device is very much like the bulb neck bending device at position eight in that the bulb is gripped by jaws 179 and 180 on levers 181 and 182 pivotally mounted on the slide 183 and are operated by movement of sub-slide 184. The device is operated through lever 185 on pin 186 in the standard 187 which engages the sub-slide through roller 188 on a pin in the end of said lever. The slide advances toward the bulb along with the sub-slide until the head of screw 189 in bracket 190 on the slide is against the head of screw 191 in bracket 192 in carriage 193. The continuing movement of the sub-slide against the pull of spring 194 causes the rollers on pin 195 to enter the widely separated part of slots 196 in plate 197 attached to the sub-slide causing said levers to be turned about pins 198. The jaws 179 and 180 are attached to these levers through clamping plates 198'. After the jaws have gripped the bulb neck, pin 199 in the end of lever 185 and yoke 200 strikes the end of slot 201 in bar 202 whereupon the carriage 193 to which the bar is attached by pin 203 is pulled down. This movement is produced against the action of springs 204 on pillars 205 over which the carriage slides and causes the bulb to be pushed or pulled down. During this movement the bulb supporting sleeve 32 slips down on spindle 33. Rod 200' is actuated by lever 206 which is in turn actuated by the engagement of a roller in its end into cam 207 on shaft 24 and actuates said rod through collar 208, collar 209 and spring 210. Lever 206 operates about pin 211 in bracket 212 attached to the pedestal 13. This device is mounted under guard 213 on table 106 and returns to its former position before the head is indexed.

At position fourteen into which the head is then indexed, the presence of the raised portion 74 (Fig. 6) of cam 69 causes the jaws 60, levers 82 and jaws 57 and 58 to open. Jaws 60 and levers 82 are opened by rollers on pins 83 which are pushed into another section of slots 84 and 85 by movement of slide 76 and jaws 57 and 58 are opened by the wedge 214 which is moved downward by cam 215 on post 78 striking roller 216 on a pin in the end of the wedge. The wedge operates in a shallow groove in plate 88 in which it is held by screw 216'. As the seal is still soft and the exhaust tube has been released by the jaws, this position should be used for any mechanism that may be applied to the machine for

locating the filament in any particular position within the bulb.

As the head is indexed from position fourteen, through position fifteen and into position sixteen, that portion of the head which has supported the mount is raised to the same level it is found at position one previously described. This action occurs as roller 67 enters the raised portion of cam 69. At position sixteen the lamp is unloaded by an air jet (not shown) which blows the lamp out into a chute after the bulb has been released of the pull of vacuum which has held it in the head. The vacuum is cut off by the port to which said head is connected in the lower half 47 of the rotary valve coming under 15 a portion of the upper half 49 of said valve in which passage 48 does not exist. The lamp unloaded at this position represents the finished product of this machine which is shown in section F of Fig. 6.

During the next indexing which carries the head from position sixteen to position one, the vacuum is again applied to the head, jaws 57 and 58 are closed and the bulb holding sleeve 32 is raised to the sealing position. This latter 25 movement is produced by the lowering and raising of spindle 33 by the reduced height of track 41 which occurs for a short distance between these positions. As the spindle lowers, sleeve 32 strikes the head of pin 217 which prevents it 30 from following the complete downward movement thereby causing it to be pushed up on the spindle into the position shown. The cam 215 is now swung clockwise away from roller 216 during the indexing motion by the striking of 35 pin 218 thereon against an arm (not shown), thereby permitting the wedge 214 to be raised as the jaws 57—58 are closed by spring 61. This movement occurs against the action of spring 219 which is stretched between a post in said 40 cam and a post in bracket 65. At a position early in the rotation of the machine when the other jaws are closed by the backward movement of slide 76 the cam is swung back against pin 220 by spring 219. The vacuum for holding 45 the bulb is applied to the head as the port in the lower half of the rotary valve is again below passage 48 in the upper half of said valve. One cycle of operation constituting one revolution of the machine has now been completely 50 described.

What we claim as new and desire to secure by Letters Patent of the United States, is:

1. The method of sealing in a bulb a mount comprising a flanged stem tube which consists in 55 inserting the mount through the open neck end of said bulb until the flange of said stem is within said bulb and holding said mount in that position, fusing that portion of the bulb neck extending beyond said flange and mechanically bending said 60 fused portion over on said flange by passing jaws laterally thereacross.

2. The method of sealing in a bulb a mount comprising a flanged stem tube which consists in inserting the mount through the open and 65 definitely sized and shaped neck end of said bulb until the flange of said stem is within said bulb and holding said mount in that position, fusing that portion of the bulb neck extending beyond said flange and mechanically bending said fused 70 portion over on said flange by passing jaws laterally thereacross.

3. The method of sealing in a bulb a mount comprising a flanged stem tube which consists in inserting the mount through the open neck end of 75

- said bulb until the flange of said stem is within said bulb and holding said mount in that position, fusing that portion of the bulb neck extending beyond said flange, mechanically bending said fused portion over on said flange by passing jaws laterally thereacross and pulling said bulb while said stem is still held to position said mount and stretch the seal formed between said bulb and said stem.
10. 4. An apparatus for sealing into bulbs mounts comprising stems which comprises a bulb holder, a stem holder, fusing fires positioned to fuse a portion of said bulb extending beyond a portion of said stem, jaws positioned to thereafter bend said fused portion over on said stem and means for actuating said jaws.
15. 5. An apparatus for sealing into bulbs mounts comprising stems which comprises a bulb holder, a stem holder, fusing fires positioned to fuse a portion of said bulb extending beyond a portion of said stem, jaws positioned to thereafter bend said fused portion over on said stem, means for actuating said jaws and mechanism for thereafter gripping said bulb and pulling the same to stretch the seal thus formed and position said mount.
20. 6. An apparatus for sealing into bulbs mounts comprising stems which comprises a vacuum bulb holder, a stem holder, fusing fires positioned to fuse a portion of said bulb extending beyond a portion of said stem, jaws positioned to thereafter bend said fused portion over on said stem and means for actuating said jaws.
25. 7. An apparatus for sealing a bulb onto a lamp mount comprising a bulb holder for holding the bulb in a neck-up position, a mount holder mounted above said bulb holder, means for lowering the mount holder so as to place a portion of the mount within said bulb, sealing fires positioned to fuse the bulb neck and jaws for bending the rim of the bulb neck over onto that portion of the mount within the bulb.
8. An apparatus for sealing a lamp mount into a bulb comprising a mount holder, a bulb holder mounted on a spindle through frictional engagement therewith, sealing fires mounted to fuse the bulb and mount held therein together and mechanism for engaging the bulb and moving the same as permitted by slippage of the bulb holder on the spindle to stretch the seal.
10. 9. The method of sealing to a lamp mount a bulb which consists in inserting through the open bulb neck a portion of the mount and with said mount uppermost, fusing the bulb neck and mechanically bending the rim thereof over onto a portion of said mount by passing jaws laterally thereacross.
15. 10. The method of sealing in a bulb a mount comprising a flanged stem tube which consists in inserting the mount through the open neck end of said bulb until the flange of said stem is within said bulb and holding said mount in that position, fusing that portion of the bulb neck extending beyond said flange and mechanically bending said fused portion over on said flange by passing jaws laterally thereacross, and subsequently further fusing said bulb neck and flange together.

JOHN F. DONOVAN.

WILLIAM L. KUBACH. 35
